UNITED STATES PATENT OFFICE

ROGER W. ROWLAND, OF NEW CASTLE, PENNSYLVANIA, ASSIGNOR TO NEW CASTLE REFRactories COMPANY, OF NEW CASTLE, DELAWARE, A CORPORATION OF DELAWARE

TUNNEL KILN CAR AND REFRACtORY SLAB THEREFOR

Application filed June 12, 1931. Serial No. 543,823.

The present invention relates to improvements in the construction of continuous tunnel kiln cars of the type having a built-up goods supporting superstructure, which comprises two or more goods supporting platforms or decks, spaced vertically by posts positioned therebetween. In use the parts forming the car superstructure are required to withstand high temperatures and to possess considerable mechanical strength. Heretofore the superstructure platforms have been composed by a plurality of flat refractory slabs of general rectangular contour longitudinally and transversely and with adjacent slabs arranged end-to-end or side-by-side and the supporting posts positioned at the corners thereof. The slabs and posts are usually made of fire clay or other highly siliceous material.

20 When cars of the above type are loaded with goods to be treated and passed through a tunnel kiln of standard design, the superstructure and goods are usually progressively heated to a high temperature and then cooled. 25 During the passage of the car through the heating section or sections of the kiln, the material forming and adjacent to the exposed surface portions of the slabs will receive more heat than the material in the center portions 30 thereof. The resulting difference in the rates of expansion of these portions of the slabs causes the latter to be subjected to internal stresses, which, when coupled with heavy load stresses, frequently results in cracking or a 35 rupture of the slab and in many cases breakage of the goods supported thereon. During the passage of the car through the cooling section of the kiln, the material forming and adjacent to the exposed surface portions of the slabs gives up heat at a greater rate than the material in the center portions thereof with a resulting difference in the rates of 40 contraction of these portions. Contraction 45 stresses consequently occur, which also tend towards a rupture of the slab structure.

The main object of my present invention is the provision of a kiln car platform slab which is light in weight, low in cost, and in 50 which all portions of the slab structure will

be subjected in use to substantially uniform heating and cooling effects.

In carrying out my invention I form each kiln car platform slab with one or more internal passages extending throughout the slab. When more than one passage is formed in each slab, all of the passages may extend in the same direction, or one or more may be arranged normal to the remaining. In assembling the slabs, I preferably arrange them on the car so that the slab passages will all extend in the same direction as the general path of the kiln chamber atmosphere, whereby the amount of the kiln chamber gases passing through the slab passages will be increased. The amount of material in the slabs is thus reduced as well as the cost of production and the weight thereof. Any reduction in weight of the superstructure elements will facilitate their handling and also decrease the amount of fuel consumed in heating these non-productive parts in the kiln.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described preferred embodiments of the invention.

Of the drawings:

Fig. 1 is an end elevation of a kiln car having a goods supporting superstructure embodying my invention;

Fig. 2 is a side elevation of the car shown in Fig. 1; and

Fig. 3 is a perspective view of a modified slab construction.

In the drawings, I have illustrated a car especially suitable for use in moving ceramic goods through a tunnel kiln of the muffle type in the direction indicated. The car as shown, comprises a body portion A which is formed in the usual manner by superposed rows of refractory blocks A' arranged on a metallic frame A², which is provided at its underside with wheels A³ for engaging

tracks B arranged in the bottom of the kiln chamber. A series of longitudinally spaced transversely extending refractory girders C are arranged on the upper row of blocks 5 A' and provide transverse circulation chambers C' through the car. The girders C serve as supports for the goods carrying superstructure of the car.

The car superstructure as shown consists 10 of a lower platform D', an intermediate platform D² and an upper platform D³, all of which are formed by a plurality of flat refractory slabs D as hereinafter described and are used for supporting ceramic goods requiring 15 treatment, as indicated in Fig. 1. The slabs D assembled to form the various platforms are preferably made of rectangular longitudinal and transverse cross-section. The assembled slabs are positioned with their 20 vertical edge portions substantially in contact. The adjacent transversely extending edge portions of each pair of adjacent slabs in the platform D' are preferably mounted on corresponding girders C. The slabs forming 25 the intermediate and upper platforms D² and D³, respectively, are mounted on the lower platform D' by posts E positioned at various spaced points thereon, preferably at the corners of the slabs.

30 When the car illustrated is employed in a downdraft muffle kiln, for example, the portions of the slabs of each platform along the longitudinal center line of the car are usually cut away or recessed to permit a 35 downflow circulation through the car and into the transverse channels C', as indicated by the arrows in Fig. 1. In kilns of this type, the kiln chamber atmosphere is circulated through the channels C' into contact with the 40 walls of combustion chambers (not shown) extending longitudinally at the sides of the kiln chamber.

When in use in a downdraft muffle kiln, the upper portion of the car superstructure is 45 usually heated to a slightly higher temperature than the lower central portion thereof. When the platform slabs are made solid, as has been heretofore the case, the material forming and adjacent to the exposed surfaces 50 of the slabs will receive a greater amount of heat than the material nearer to the centers of the slabs, while the car is passed through the heating sections of the kiln. A corresponding difference in the rates of expansion 55 of these portions of each slab consequently occurs and invariably causes stresses to be set up in the slab which, if sufficiently great, will cause a rupture in the slab structure. With solid slabs arranged as described, these 60 stresses are greatest in the portion of the slabs on which the goods are positioned. The presence of heavy loads coupled with expansion strains usually results in the formation of cracks in the slab structure and not infrequently in a rupture of the slab while in the

65 kiln, damage to goods on the car, and possibly interference with the car movements. During the passage of the cars through the 70 cooling section of the kiln, contraction strains will occur in each slab due to the differences in the rates at which the different portions give off heat, with results similar to those just described. In general, the slabs in the 75 platforms D', D², D³, increase in the order named in their liability to damage from the above causes.

In accordance with my present invention, 80 each of the slabs having a liability for rupturing because of differences in the rates of expansion or contraction of different portions thereof is formed with one or more horizontal 85 passages D⁴, which extend through the portion of the slab which has heretofore had the lowest rate of expansion or contraction. With slabs of the shape illustrated, the 90 passages D⁴ are of considerably greater width than depth and preferably symmetrically arranged relative to one of the center lines thereof. When the slabs are arranged as 95 shown in a kiln in which the circulation of the kiln chamber atmosphere is transverse to the kiln length, the passages D⁴ are advantageously formed and/or arranged in the slabs so as to extend transversely of the car and parallel to the channel C'. When the 100 main circulation is longitudinally of the kiln chamber, as in a direct fire kiln, a longitudinal 105 positioning of the passage D⁴ is preferable. When so arranged in parallel with the path of flow of the heating gases, a greater amount of the circulating kiln atmosphere will pass through the passages in both the 110 heating and cooling sections of the kiln.

In the slab construction shown in Figs. 1 and 2, two passages D⁴ are formed in each slab and symmetrically arranged at opposite sides of the center line and parallel to the transverse side edges thereof. When two such slabs are used for the width of the car, their 115 respective passages will be in alignment. In the slab shown in Fig. 3, only one passage D⁴ is shown extending through the longer horizontal portion thereof, while two similar passages D⁴⁰ are symmetrically arranged normal to and intersecting the passage D⁴. The 120 proportioning of the slabs depends largely upon the size of the kiln car on which they are to be used, while the arrangement of the slab 125 passages depends primarily on the operating conditions to which they are to be subjected. The slabs may be so formed by a suitable casting, pressing, ramming or extruding operation and thereafter fired.

When in use, the slab passages will generally have a circulation therethrough sufficient in amount to cause the material in the portions of the slab surrounding the passages to be always subjected to substantially the same temperature conditions as the material forming and adjacent to the exposed 130

surfaces thereof. All portions of the slabs will then have substantially the same rates of expansion and contraction with a consequent elimination of internal strains in the slab structure.

The described slab formation is also advantageous in reducing the amount of material used in making the slabs with a consequent reduction in the cost of production and weight of the slabs. Any decrease in slab weight advantageously increases the ratio of the weight of goods being treated to the weight of the unproductive superstructure elements and thereby lowers the amount of fuel consumed in heating these elements. The decrease in weight also facilitates the handling of the slabs when such operations are necessary in loading or unloading the goods.

While in accordance with the provisions of the statutes, I have illustrated and described the best forms of embodiment of my invention now known to me, it will be apparent to those skilled in the art that changes may be made in the forms of the constructions disclosed without departing from the spirit of my invention as set forth in the appended claims and that in some cases only the slabs in the upper platform need be made in the manner described.

Having now described my invention, what I claim as new and desire to secure by Letters Patent, is:

1. A kiln car having a goods supporting superstructure comprising a plurality of vertically spaced goods supporting platforms, each formed by a horizontally arranged goods supporting refractory slab structure, one of said slab structures having a horizontal passage extending therethrough and arranged parallel to the direction of circulation of the kiln chamber atmosphere.

2. A kiln car having a goods supporting superstructure comprising a plurality of vertically spaced goods supporting platforms, each formed by a plurality of horizontally arranged goods supporting refractory slabs of oblong cross-section supported on posts, some of said slabs having one or more shallow horizontal passages of substantial width opening to opposite sides thereof and arranged for the passage therethrough of the kiln chamber atmosphere.

3. A muffle kiln car having a goods supporting superstructure comprising a plurality of vertically spaced goods supporting platforms, each formed by a plurality of horizontally arranged flat goods supporting refractory slabs, said platform slabs having horizontal passages extending transversely of said car to permit the circulation therethrough of the kiln chamber atmosphere.

4. A kiln car goods supporting platform slab of rectangular cross-section and formed of refractory material, and having a hori-

zontal passage of substantial width and relatively small height formed therein and opening at opposite ends thereof, said passage being symmetrically arranged relative to the other pair of opposite edge portions of said slab.

5. A kiln car goods supporting platform slab of substantially oblong cross-section and formed of refractory material, and having a plurality of horizontal passage of substantial width and relatively small height formed in a slab portion otherwise having relatively low rates of expansion and contraction, said passages opening to opposite sides of said slab.

6. A kiln car goods supporting platform slab or rectangular form and made of refractory material, and having a plurality of horizontal passages formed therein and opening at opposite edge portions thereof, two of said passages being arranged normal to one another and intersecting.

Signed at New Castle, in the county of Lawrence and State of Pennsylvania, this 2nd day of June, A. D. 1931.

ROGER W. ROWLAND.
